UNITED STATES PATENT OFFICE.

GEORGE E. RIGHTNOUR, OF KEARNEY, PENNSYLVANIA.

JOINT AND CHAIR FOR RAILWAY-RAILS.

1,346,384.

Specification of Letters Patent. Patented July 13, 1920.

Application filed May 12, 1920. Serial No. 380,748.

To all whom it may concern:

Be it known that I, GEORGE E. RIGHTNOUR, a citizen of the United States of America, residing at Kearney, in the county of Bedford and State of Pennsylvania, have invented certain new and useful Improvements in Joints and Chairs for Railway-Rails, of which the following is a specification.

10 The primary object of the invention is the provision of a strong and simple joint for railway rails obviating the necessity of bolts, nuts and similar hold-fast devices, the joint being easily and quickly assembled mounted upon the ties ready for use.

15 A further object of the invention is to provide a strong means of connecting adjacent ends of rails together producing a firm lock and presenting a substantially unbroken tread surface for the travel of rolling stock thereover, the shock of the wheels when passing the joint being prevented.

20 A still further object of the invention is to provide an interlocking end joint for railway rails and means for mounting the same upon the ties without using fish-plates or bolts, thereby saving expense as well as the time in laying and repairing railway tracks.

25 With these general objects in view and others that will appear as the nature of the invention is better understood, the same consists in the novel construction, combination and arrangement of parts hereinafter more fully described, illustrated in the accompanying drawings, and pointed out in the appended claims.

30 In the drawings forming a part of this application and in which like reference characters refer to corresponding parts throughout the several views,

35 Figure 1 is a side elevation of my form of joint and mounting means illustrating the same positioned upon two adjacent railway ties,

40 Fig. 2 is a top plan view thereof, showing the uninterrupted tread portions of the rails,

45 Figs. 3 and 4 are vertical transverse sectional views taken upon lines III—III and IV—IV of Fig. 1,

50 Fig. 5 is a perspective view of the form of end portion provided upon one of the inter-engaging rails,

Fig. 6 is a similar view of the adjacent end portion of the coöperating rail and

Fig. 7 is an inverted perspective view of the mounting chair or bed-plate employed with the joint.

It will be understood that my form of joint is serviceable for track rails of different kinds, for both railroads as well as mines and other places where the quick laying of temporary tracks is found desirable.

The interlocking male and female ends of two adjacently positioned rails will be described it being understood however that each rail has its opposite ends formed in said different manners so that the continuous line of track is easily and quickly positioned together.

Two adjacent ties 10 are herein illustrated of the usual form provided transversely of the road-bed, a rectangular bed-plate or chair 11 being positioned thereon for spanning said ties with marginal flanges 12 upon its upper face for the reception therebetween of the base flanges of the engaging ends of adjacent rails 13 and 14. The lower face of the plate 12 has roughened portions 15 in the form of spaced grids which engage the tops of the ties 10 and prevent the slipping or creeping of the plate 11 upon the ties.

The rail end 13, termed the male member, possesses the usual form of a railway rail having a web 16 connecting the tread 17 with the base or flanges 18 thereof. The base flanges and web are cutaway or terminate in an end face 19 of inverted T-shape form while the tread 17 is continued or extended as at 20 having a terminal tongue 21 provided with an oval-shaped head 22, the sides 23 of which are downwardly convergent or tapered. The tongue 21 is of less thickness than the tread 20 and is cutaway at one side as at 24, thereby forming a shoulder or face 25 at the end of the tread 20, at one side of and beneath the tongue 21. The tread extension 20 has a central longitudinal slot 26 upon its lower face of the same width as and terminating adjacent the cutaway end of the web 16.

100 The coöperating rail end 14 or female end portion, comprises a similar rail having a web 16' connecting the tread 17' thereof with the base flanges 18', the tread portion 17' of the end 14 however being cut away or terminating as at 27 while the base flanges 18' are extended in terminal portions 28 and the web 16' is similarly ex-

tended in an end portion 29 providing an inverted T-shaped end face 19' spaced from the tread end 27.

When the rail ends 13 and 14 are positioned in longitudinal alignment, the T-shaped faces 19 and 19' are adapted for substantially abutting engagement, the web portion 29 being extended upwardly above the lower edge of the tread 17' after the nature 10 of a rib received within the slot 26 of the tread 17 of the co-operating end 13. The end portion of the tread 17' is provided with a recess or cutaway portion 30 complementally formed in respect to the tongue 21, 15 providing an oval tapered socket 31 for the reception of the head 22, the said tongue 21 with its head being adapted to seat upon the bottom 32 of the recess 30 when the joint is assembled.

20 The tapering of the head 22 and socket 31 permits the ends to be assembled only upon relative vertical movements of the ends 13 and 14, the oval-shape of the head 22 and socket 31 preventing the rail from being connected or becoming disconnected by any relative longitudinal movements of the rails.

25 Lateral strains are taken up by the web portion 29 fitting in the slot 26 so that the web portion of the joint possesses great strength and eliminates a complete transverse break or crack between the abutting ends of the treads of the rails as is usually the case.

The face 25 of the tread 20 engages the 30 end face 27 of the tread 17' while one side of the recess 30 is broken away forming an end face 27' at the opposite side of the recess, from the face 27 but in a different vertical plane and adapted for engagement by the 40 end face 25' provided upon the tongue 21 in the nature of a shoulder.

With the rail ends 13 and 14 in their engaging positions as illustrated in Figs. 1 and 2 of the drawings, and the base flanges 18 and 28 thereof mounted upon the plate 11 between its sides 12, the rails are firmly connected together and in position for use upon the ties 10.

Spikes 33 are adapted to be driven 50 through side notches 34 in the base flanges of the rail ends 13 and 14 and also through perforations 35 in the plate 11 for embedding the spikes in the ties 10 and holding the rail ends and plate 11 upon the ties as 55 well as holding the rails joined together in locked relations.

A rail joint of great strength is provided which taken with the chair or base plate 11 provides a complete coupling means for rails 60 that is inexpensive, easily assembled and disassembled, but impossible of becoming accidentally disconnected.

What I claim as new is:—

1. A joint for rail ends comprising a 65 rail having the web and base flanges thereof

cutaway at one end of the rail and with the tread extended with a central longitudinal slot in the bottom of the extended tread portion of the same width as and terminating adjacent the end face of the web, a 70 tongue at the end of said tread extension of less thickness than such extension and cutaway in different vertical planes at its opposite sides forming shoulders out of alignment with each other, the tongue having an oval-shaped terminal head of tapered formation, a complementally formed adjacent rail end having its tread cutaway with a receiving recess in the top thereof for said tongue and head with abutting portions of 80 said shoulders and with the web portion upwardly extended positioned within the said slot when the joint is assembled.

2. A joint for rail ends comprising a rail having the web and base flanges thereof 85 cutaway at one end of the rail and with the tread extended with a central longitudinal slot in the bottom of the extended tread portion of the same width as and terminating adjacent the end face of the web, a tongue 90 at the end of said tread extension of less thickness than such extension and cutaway in different vertical planes at its opposite sides forming shoulders out of alignment with each other, the tongue having an oval-shaped terminal head of tapered formation, a complementally formed adjacent rail end having its tread cutaway with a receiving recess in the top thereof for said tongue and head with abutting portions of 95 said shoulders and with the web portion upwardly extended positioned within the said slot when the joint is assembled, a mounting plate for the rail ends provided with grid portions on its under side adapted for 100 seating upon spaced transverse ties, side flanges upon said plate between which the base flanges of the rail ends are positioned and retaining spikes extending through said plate in engagement with the base flanges 110 of the rail ends, when the rails are assembled for use in longitudinal alignment.

3. A rail joint comprising a rail end having the terminal portion of the tread thereof cutaway with the adjacent portion of the 115 web extended upwardly forming a receiving portion, the terminal portion of the tread having a recess in its upper face with an oval tapered socket portion in the tread at the inner end of the recess and with one side 120 of the recess cutaway providing a shoulder portion for the tread spaced from the free end of the tread, a complementally formed rail end having its web and base flanges cutaway with a projecting tread portion provided with a bottom slot in which said upwardly extended web portion is seated when the joint is assembled and a tongue member upon the end of the extended tread portion formed complemental relatively of said re- 130

cess adapted for seating in said recess upon relative vertical movements of the rail ends and including a tapered oval head adapted for reception within said socket portion of the recess and end faces out of alignment with each other adapted for abutting said shoulder portions of the cutaway head at opposite sides of the recess therein as set forth and described.

10 4. A rail joint comprising a rail end having the terminal portion of the tread thereof cutaway with the adjacent portion of the web extended upwardly forming a receiving portion, the terminal portion of the tread having a recess in its upper face with an oval tapered socket portion in the tread at the inner end of the recess and with one side of the recess cutaway providing a shoulder portion for the tread spaced from the free end of the tread, a complementally formed rail end having its web and base flanges cutaway with a projecting tread portion provided with a bottom slot in which said up-

wardly extended web portion is seated when the joint is assembled and a tongue member 25 upon the end of the extended tread portion formed complementally relatively of said recess adapted for seating in said recess upon relative vertical movements of the rail ends and including a tapered oval head adapted 30 for reception within said socket portion of the recess, end faces out of alignment with each other adapted for abutting said shoulder portions of the cutaway head at opposite sides of the recess therein, a base plate having marginal flanges between which the base flanges of the coöperating rail ends are adapted to seat with said ends mounted upon the plate when the joint is positioned for use and holdfast devices positioned 35 through the base flanges of the rail ends and through said plate whereby the rails are secured in position when the device is assembled.

In testimony whereof I affix my signature. 45
GEORGE E. RIGHTNOUR.
